ATTORNEYS.

UNITED STATES PATENT OFFICE.

CHARLES S. FRANKE, OF BROOKLYN, NEW YORK.

BUTTON.

SPECIFICATION forming part of Letters Patent No. 487,389, dated December 6, 1892.

Application filed May 24, 1892. Serial No. 434,119. (No model.)

To all whom it may concern:

Be it known that I, CHARLES S. FRANKE, of Brooklyn, Kings county, New York, have invented an Improved Button, of which the following is a specification.

This invention relates to a button for ladies' jackets and for other purposes, which can be readily opened and can be easily attached to the garment.

10 It consists in the various features of improvement more fully pointed out in the claims.

In the accompanying drawings, Figure 1 is a face view of my improved button; Fig. 2, 15 a rear view thereof with the back-plate and covering removed; Fig. 3, a cross-section through the button; Fig. 4, a face view of the back-plate *g*; Fig. 5, a cross-section thereof; Fig. 6, a face view of the fastening-plate *h*; 20 Fig. 7, a cross-section thereof; Fig. 8, a face view of the washer *j*; Fig. 9, a cross-section thereof; Fig. 10, a face view of the head *c*; Fig. 11, a face view of the fastening-plate *h*; Fig. 12, a cross-section thereof; Fig. 13, a face 25 view of washer *j*', and Fig. 14 a longitudinal section through needle *k*.

In Figs. 1 to 10 the letter *a* represents the lock-case, which may be inclosed by a suitable fur or other flexible covering *b*. The 30 flange *a'* of the lock-case *a* is slotted at three places, Fig. 2—viz., at *a*² for the reception of the laterally-entering head or catch *c* and at *a*³ *a*³ for the outward passage of a pair of sliding push-pins *d*. These push-pins have 35 enlarged inner ends, which prevent the pins from falling out of the lock-case. The enlarged inner ends of the push-pins bear against the pivoted locking-plates *e*. These locking-plates have hook-shaped ends opposite the slot *a*², that are adapted to grasp the head *c* as it enters through the slot. To open 40 the button, the pins *d* are pressed inward to revolve the locking-plates and cause them to release the head *c*. As soon as pressure on 45 the push-pins is released the jaws of the locking-plates are again forced together by the locking-spring *f*, ready for the next introduc-

tion and engagement with the head *c*. The outwardly-projecting ends of the push-pins *d* should be concealed by the flexible covering 50 *b*, Fig. 3, so that the button does not expose any of its operating mechanism.

To attach the button to the garment and the flexible covering to the button, I secure to the back-plate *g* a fastening-plate *h* by means 55 of flaps *g'*, struck out of the back-plate. These flaps enter slots *h'* in the fastening-plate and are upset to hold the parts together. The fastening-plate *h* is provided with a pair of prongs, pins, or fasteners *i*. These prongs 60 are thrust through the garment *A* and then a perforated washer *j* is slipped over their exposed ends, after which they are upset to attach the button in place.

In case the button is to be attached to a 65 heavy or thick material—such as leather or fur—I make use of the fastening illustrated in Figs. 11 to 14. Here the fastening-plate *h*² is provided with a hollow pin *i*', composed of three disconnected plates, forming a truncated 70 cone. Over this cone is slipped a triangular needle *k*, which is forced through the garment, taking the pin *i*' with it. Next the needle is removed, a washer *j*' is slipped over the pin, and then the plates constituting the 75 pin are bent apart to fasten the button in place.

What I claim is—

1. The combination of case *a*, with locking- 80 plates *e*, push-pins *d*, spring *f*, back-plate *g*, having projections *g'*, a fastening-plate *h*, having a pin, and a flexible cover that incloses the case and push-pins, substantially as specified.

2. The combination of case *a*, with locking- 85 plates *e*, spring *f*, push-pins *d*, and with back-plate *g*, having projections *g'*, fastening-plate *h*, having slots *h'*, and a pin secured to the fastening-plate, substantially as specified.

CHARLES S. FRANKE.
